Viktor Schreckengost, Cleveland Heights, Ohio, assignor to The Murray Ohio Manufacturing Company, Cleveland, Ohio, a corporation of Ohio

Application May 28, 1956, Serial No. 41,666

Term of patent 14 years

(Cl. D62—4)

Fig. 1.

Fig. 1 is a perspective view of a window fan embodying my new design, illustrating the front, top and one side thereof;

Fig. 2 is an enlarged top plan view thereof; and

Fig. 3 is an enlarged fragmentary portion illustrating the design detail of the front decorative strip. The back of the window fan is without ornamentation and the side not shown is the same as the side shown.

I claim:

The ornamental design for a window fan, substantially as shown and described.
